GAS AND LIQUID SEPARATOR

Charles R. Neeson, Oakwood, Ohio, assignor to
 Chrysler Corporation, Highland Park, Mich.,
 a corporation of Delaware

Application August 31, 1946, Serial No. 694,323

1 Claim. (Cl. 183—42)

1

My present invention relates to a device for separating suspended liquid particles from a gas, the device being of particular utility in refrigerating systems as a means for separating suspended oil particles from a refrigerant gas under compression. Other uses may be found for the device and it is not intended to limit the use of the invention to a refrigeration system.

The principal object of my invention is to provide a separator wherein all of the effects usually employed to separate liquid from gas are found in one simple combination. In my invention the liquid particles are separated by centrifugal effect, by coherence, by scrubbing or screening action, and by the effect of gravity upon the liquid particles in an area through which the gas travels at low velocity.

A further object of my invention is to provide a liquid separator made of relatively simple parts of relatively simple manufacture.

The foregoing and other objects and advantages of my invention will be more readily apparent from a study of the following specification taken in connection with the accompanying drawings wherein like numerals refer to like parts throughout. In the drawings Fig. 1 is a vertical longitudinal section of the device; and Fig. 2 is a partial section taken substantially along line 2—2 of Fig. 1 and looking in the direction of the arrows.

My invention comprises a substantially cylindrical shell 10 which is adapted to be located with its longitudinal axis in a vertical plane. The shell is preferably made by uniting the edges of two substantially identical cup-shaped members 11 and 12 as by means of welding circumferentially as at 13. Other means of uniting the cup-like sections may be employed but I prefer the welding because of simplicity of manufacture. The sections 11 and 12 may be stamped or drawn as identical members by the same forming mechanism, their edges trimmed, and the two sections stored in a common bin before further fabrication.

Before uniting the two sections the section 11 is provided with an opening in a wall thereof adapted to receive the reduced end 15 of an inlet connection 16, and the section 12 is provided with an opening adapted to receive a liquid outlet connection 17. The diameters of the portion 15 and the connection 17 are preferably the same so that the openings through the sections may be drilled or punched by the same tool, and the openings are preferably at the same distance from the lip of the section so that the forming

2

thereof may be accomplished in the same fixture or drilling jig. Thereafter the sections 11 and 12 may still be placed in a common bin since there is yet no difference between the two.

At this point in the fabrication of the device one-half of the cup-like sections are provided with a central opening adapted to receive the reduced end 18 of a gas outlet connection 19, the diameter of the opening being the same as the diameters of the previous openings for the same reasons.

The connectors 16 and 19 may be formed as substantially identical members except that the longitudinal opening through member 16 does not extend entirely through the member whereas the opening through the member 16 does so extend. As seen more clearly in Fig. 2 the opening 20 through the member 19 terminates short of the inner end 21 and the outlet therefrom comprises a transverse slot 22 such as would be formed by a saw or milling cutter, extending half way through the member 16. The member 16 may be formed identically the same as member 19 except that the reduced portion 15 thereof is sufficiently long in comparison to the reduced portion 18 of member 19, that a drill set to descend a certain distance will pass entirely through the member 19 whereas it will not pass through the member 16. The members 16 and 19 may be attached to the section 11 as by means of welding at 24 and 25 respectively. The member 17 similarly is attached to the section 12 and by welding at 26.

A sub-assembly comprising a shelf forming member 28, a cylindrical screening member 29 and a locating member 30 is formed by combining the three members as illustrated in Fig. 1. The shelf forming member preferably comprises a horizontal portion terminating in an outer upwardly extending flange 31 of outer diameter to fit snugly within the shell 13, and an inner annular step 32 adapted to receive the screen member 29, the shelf surrounding a large central aperture 33. The locating member 30 preferably comprises a central horizontal portion surrounding a restricted central aperture 34, and a stepped outer portion adapted to receive the upper end of the screen member 29. The screen member 29 preferably comprises a cylindrical roll of several layers of screen material as illustrated, the layers being closely superimposed so as to form a substantially rigid sustaining cylinder. The members 28, 29 and 30 are preferably joined together as by means of spots of solder as at 36, at least sufficient thereof being provided

to retain the members in assembled relation until final assembly thereof with the shell section 11. The sub-assembly so formed may be inserted in the shell section until the locating member 34 strikes the top of the section, whereupon the member 28 may be tack-welded to the shell as at 37. If the heat of welding should melt the solder connecting the members 28 and 29 they will nevertheless be retained in assembled relation by the shouldered flange 32. An alternative form of assembly would be to weld the member 30 in position, to insert the member 29 as a separate member and to thereafter insert the member 28 as a separate member which is then welded to the section 11. Choice of either method may depend upon the fabricating cost with the facilities available, and in either event screen member 29 will be located and retained in proper position.

The screen member 29 is preferably formed of relatively coarse mesh woven wire screen, such as of the order of 16 to 20 meshes to the linear inch. A single layer of such material would undoubtedly pass particles in suspension, but by rolling a strip of such material upon itself a plurality of times there will be such overlapping of the mesh forming material as to form a plurality of labyrinthine passages causing the gas to swirl and eddy upon itself as it passes through the cylindrical member. The moisture particles in suspension will moisten the mesh forming material and will attract other particles to cohere therewith to form larger droplets which will tend to run down between the layers of material or on the outer and inner surfaces of the member 29.

The outer diameter of the member 29 is preferably such as to provide an annular space 43 entirely enclosed between the shell section 11, the screen 29 and the shelf 28 except for the inlet opening 22 and the passages through the screen material. The member 16 is so connected to the cup section 11 that the opening 22 extends substantially tangentially of the inner surface of the shell section 11. Gas and liquid mixture projected under compression and at high velocity through the opening 22 will whirl around the annular space 43, thus causing the heavy liquid particles to tend to separate outwardly by centrifugal effect. The particles will wet the inner wall of the section 11, thus causing other particles to cohere therewith until droplets are formed which will run down the inner wall.

The inner diameter of the screen section 29 is preferably quite large with respect to the diameter of the opening 22 and of the outlet through member 19 so that the gas which passes through the member 29 will travel through the inner space at considerably reduced velocity. In this area of comparative quiescence any droplets which may remain suspended in the gas tend to separate by falling through the opening 22 under the effect of gravity.

The member 17 is provided with an inner threaded opening in which is seated a valve seat such as member 45. A bracket member 46 is attached to the inner end of member 17 and a lever 47 is pivoted thereto at 48. The lower end of the lever carries a valve 49 adapted to seat in the opening of the valve seat 45. The upper end of the lever 47 is attached to a ball float 50 as by means of a screw 51 threaded into a plug 52 of deformable material such as lead, the plug 52 thereby providing weighting means for the float, a seat for the screw 51 and a seal for the opening

in the ball. Other types of float, float leverage, and valve may be substituted for those shown.

After assembly of the separating means with the cup section 11 and of the valve mechanism 5 with the cup section 12 the sections may be united as shown and described to form the complete separator.

The operation of my device is as follows: A source of gas and liquid in suspension therein is connected to the inlet member 16, an outlet tube for the gas is connected to the member 19 and an outlet tube for the liquid is connected to the member 17. In the usage for which the device is most adapted at the present time, member 16 10 will be connected to the outlet of a compressor, member 19 will be connected to the refrigeration system leading back to the compressor, and member 17 will be connected to the oil reservoir of the compressor. As is well known in the refrigeration art particles of oil are usually suspended in the compressed gas. These particles 20 will be separated from the gas by the centrifugal effect in space 40, by the cohering or wiping or scrubbing effect of the walls and 25 screen member 29 and by the effect of gravity in the central space. The oil so collected falls into the bottom section 12 to form a pool therein. When the level of the pool covers the valve opening 30 49 from its seal and the pressure of the gas will cause return of the oil to the compressor.

It is to be noted that the member 28 is welded to the cup section 11 at a distance from the edge or rim of the section. If for any reason it should 35 become necessary to inspect the interior of the separator for adjustment or replacement of parts the device may be placed in a lathe or other cutting machine and the section separated by cutting away the weld 13 and the edges adjacent thereto. 40 After repair the two sections may then be rejoined. Sufficient material is provided so that this may be done at least once or possibly several times without causing the float 15 to bind against the apertured member 28.

45 A further advantage of the device is that any foreign particles such as core sand or metal filings which may have been left in the compressor will be permanently trapped between the screen member 29 and the wall of section 11. Also any fine 50 grit which may find its way through the screen will tend to fall into and be trapped in the quiet pool of oil at the bottom of member 12.

Having illustrated and described the preferred form of my invention it should be apparent to those skilled in the art that various modifications in detail and arrangement thereof may be divided without departing from the spirit of my invention. I claim as my invention all such modifications as come within the scope of the following claim.

I claim:

A device for separating suspended liquid particles from a gas, comprising a housing having upper and lower walls and a cylindrical side wall, 65 said housing being adapted when in use to be located with its longitudinal axis extending in a substantially vertical direction, partition means in said housing forming an upper and a lower chamber therein, said partition having an aperture therein, said lower chamber being adapted to serve as a reservoir for said liquid, means associated with the side wall of said upper chamber and forming an inlet for liquid and gas to be separated, said means being adapted to direct 70 the entering liquid and gas in a direction sub-

stantially tangential to said cylindrical upper chamber to thereby induce motion of the liquid and gas in the upper chamber in a vortex so that liquid will be separated from said gas by centrifugal force and accumulate on the side wall of said upper chamber, said housing having an outlet formed in the top wall thereof and aligned with said axis, said outlet being adapted to serve as a discharge orifice for said gas, a cylindrical filter element formed of pervious material positioned coaxially of said cylindrical housing in said upper chamber and having a lateral dimension larger than said discharge orifice but less than the diameter of said upper chamber so that gas and liquid which are swirling and moving toward the center of said vortex attempt to penetrate said pervious filter material and the gas penetrates the pervious filter material and is withdrawn upwardly through said outlet while liquid collects on the filter and drops by gravity

into said lower chamber and any liquid which penetrates the filter drops by gravity to said lower chamber as the gas is withdrawn upwardly toward said outlet.
